CLAIM

The ornamental design for a plant flat, as shown and described.

DESCRIPTION

FIG. 1 is a top plan view of a plant flat first embodiment of our new and ornamental design;

FIG. 2 is an enlarged sectional view taken along lines 2—2 of FIG. 1;

FIG. 3 is a bottom plan view of the first embodiment;

FIG. 4 is an end elevation view of the first embodiment, the opposite end being identical;

FIG. 5 is a top plan view of a plant flat second embodiment of our new and ornamental design;

FIG. 6 is an enlarged sectional view taken along lines 6—6 of FIG. 5;

FIG. 7 is a bottom plan view of the second embodiment;

FIG. 8 is an end elevation view of the second embodiment, the opposite end being identical;

FIG. 9 is a top plan view of a plant flat third embodiment of our new and ornamental design;

FIG. 10 is an enlarged sectional view taken along lines 10—10 of FIG. 9;

FIG. 11 is a bottom plan view of the third embodiment; and,

FIG. 12 is an end elevation view of the third embodiment, the opposite end being identical.
